ABSTRACT OF THE DISCLOSURE

Mixtures of 1,1,1-trifluoroethane and chloropentafluoroethane. These mixtures behave like an azeotrope, and they boil in the range of —55° F. to —57° F. They are useful as refrigerant compositions.

This invention relates to refrigerant compositions and more particularly to mixtures of 1,1,1-trifluoroethane and chloropentafluoroethane which have azeotrope-like characteristics and are useful as low-boiling refrigerants.

The mixed fluorine and chlorine derivatives of methane and ethane have attained widespread use in refrigeration as a result of their low toxicity and chemical inertness and the low specific volumes and range of boiling points possessed by various members of the series. Trichlorofluoromethane [B.P. 74.8° F. (23.8° C.)], dichlorodifluoromethane [B.P. —21.6° F. (—29.8° C.)], chlorodifluoromethane [B.P. —41.4° F. (—40.8° C.)], 1,2-dichlorotetrafluoroethane [B.P. 38.8° F. (3.8° C.)], and chloropentafluoroethane [B.P. —37.7° F. (—38.7° C.)] represent the most commonly used compounds of this type. Mixtures of some of these compounds in certain proportions are azeotropes. For example, Benning, in U.S. Patent 2,641,579, discloses that a mixture of 49% by weight of chlorodifluoromethane and 51% by weight of chloropentafluoroethane is an azeotrope having a normal boiling point of —50° F. (—45.6° C.) and Lewis, in U.S. Patent 2,641,580, discloses that a mixture of 84% by weight of chloropentafluoroethane and 16% by weight of 1,1-difluoroethane is an azeotrope having a normal boiling point of —42.2° F. (—41.3° C.). On the other hand, French Patent 1,320,327 discloses that mixtures of 46% to 69% by weight of difluoromethane and 54% to 31% by weight of chloropentafluoroethane form two liquid phases having boiling point of about —70.6° F. (—57° C.).

An azeotrope is a mixture of two mutually soluble compounds which has a constant boiling point and a constant distillate composition. The formation of azeotropes cannot be predicted although many attempts have been made to do so. Azeotropes are valuable in many cases because they possess beneficial properties which are not possessed by either of the components of the mixture.

Refrigerants having a wide range of boiling points are needed to allow the design of efficient equipment for various refrigerating demands. The choice of equipment should be made in light of the temperature to be reached, the power cost, the cost of the equipment, and the requirements of space. Increased efficiency of operation and flexi-

2

bility of design become possible when additional refrigerants of suitable properties are developed.

Although equipment designed to use a particular refrigerant is installed, the need for increased refrigerating capacity sometimes arises. Such a need may be filled with a refrigerant having a lower boiling point and resultant higher vapor pressure at the temperature of the gas before it is compressed and liquefied. It is not practical, however, to use a refrigerant having a boiling point too much lower than that for which a given apparatus has been designed because the power input becomes too high and the compressor motor becomes overloaded. To provide increased refrigerating capacity, for example, for equipment designed for chlorodifluoromethane without excessive change in power input, a gas which is liquefied somewhat below the boiling point of this refrigerant may be used.

It is, therefore, an object of this invention to provide low boiling compositions which are useful as refrigerating agents. Another object is to provide an azeotropic mixture which is effective in low temperature refrigerating installations. A further object is to provide a refrigerant which may be used to give greater refrigerating capacity with equipment designed for use with chlorodifluoromethane. A still further object is to provide a refrigerant which operates with a smaller temperature rise on compression than chlorodifluoromethane to ensure against overheating, insulation failure, electrical burnout, and mechanical failure. Other objects are to provide new compositions of matter and to advance the art. Still other objects will appear hereinafter.

The above and other objects may be accomplished in accord with this invention by the low-boiling refrigerant compositions which consist of mixtures of from about 40% to about 75% by weight of 1,1,1-trifluoroethane and from about 60% to about 25% by weight of chloropentafluoroethane.

It has been found that 1,1,1-trifluoroethane and chloropentafluoroethane form a minimum boiling point azeotrope consisting of 60% by weight of 1,1,1-trifluoroethane and 40% by weight of chloropentafluoroethane having a normal boiling point of -56 ± 1 ° F. (-50 ± 0.5 ° C.), compared with the normal boiling points of —47.5° C. for 1,1,1-trifluoroethane and —38.7° C. for chloropentafluoroethane. It has been found further that the mixtures of 40% to 75% by weight of 1,1,1-trifluoroethane and 60% to 25% by weight of chloropentafluoroethane have normal boiling points in the range of —55° F. to —57° F. (—48.3° C. to —49.5° C.) at a pressure of 14.7 p.i.s.a., which are below the boiling points of the individual components of the mixtures, and that such mixtures have azeotrope-like characteristics.

The mixtures (compositions) of this invention are very useful as refrigerants and particularly are useful in refrigeration apparatus designed for use with chlorodifluoromethane as the refrigerant when greater refrigeration capacity is desired or when lower heats of compression are needed.

In the following Table I, there is given the data obtained with tests comparing the azeotrope of this invention with chlorodifluoromethane.

TABLE I.—CALORIMETER DATA COMPARING THE AZEOTROPE $\text{CH}_3\text{CF}_3/\text{CCl}_2\text{CF}_3$
60/40 BY WEIGHT AND CHClF_2
Condensing Temperature, +110° F.; Return Gas Temperature, +65° F.

	Evaporator Temp., ° F. (° C.)	$\text{CH}_3\text{CF}_3/\text{CCl}_2\text{CF}_3$, 60/40	CHClF_2	Ratio to CHClF_2
Compressor Capacity, B.t.u./hr.	+20 (-6.7)	44,700	40,510	1.10
	-20 (-28.9)	15,900	12,990	1.22
	-40 (-40)	7,230	5,700	1.27
Ratio of Compression	+20	3.90	4.20	0.93
	-20	8.75	9.70	0.90
	-40	13.70	15.80	0.87
Difference from CHClF_2				
Compressor Discharge Temp., ° F. (° C.)	+20	190 (88)	226 (108)	-36
	-20	253 (123)	320 (160)	-67
	-40	284 (140)	356 (180)	-72
Motor Temp., ° F. (° C.)	+20	115 (46)	111 (44)	+4
	-20	120 (49)	148 (64)	-28
	-40	149 (65)		

From these tests, it will be apparent that the azeotrope is superior in compressor capacity, especially at low evaporator temperatures, and ratio of compression. The azeotrope also exhibits important advantages relative to compressor discharge temperature and motor temperature.

There are only slight changes in the boiling point when the composition is varied over a substantial range on either side of the azeotropic composition. Thus, there is little tendency for fractionation to take place with any of these mixtures and most of the advantages shown in Table I for the azeotrope are retained. Over the composition range of from 40% to 75% by weight of 1,1,1-trifluoroethane and 60% to 25% by weight of chloropentafluoromethane the boiling points of the mixture are lower than that of 1,1,1-trifluoroethane.

In addition to having significant advantages over chlorodifluoromethane as described, the compositions of this invention can be used in place of the azeotrope of chlorodifluoromethane and chloropentafluoromethane (a refrigerant now on the market). Compared with this azeotrope, the azeotrope of this invention is slightly superior in having a higher capacity and in having a lower compressor discharge temperature and motor temperature. It has a comparable performance factor. The pertinent data are presented in Table II.

TABLE II.—CALORIMETER DATA COMPARING THE AZEOTROPE $\text{CH}_3\text{CF}_3/\text{CCl}_2\text{CF}_3$ 60/40 BY WEIGHT
AND THE AZEOTROPE $\text{CHClF}_2/\text{CCl}_2\text{CF}_3$ 49/51 BY WEIGHT
Condensing Temperature, +110° F. (43.3° C.); Return Gas Temperature, +65° F. (18.3° C.)

	Evaporator Temp., ° F. (° C.)	$\text{CH}_3\text{CF}_3/\text{CCl}_2\text{CF}_3$, 60/40	$\text{CHClF}_2/\text{CCl}_2\text{CF}_3$, 49/51	Ratio to $\text{CHClF}_2/\text{CCl}_2\text{CF}_3$
Compressor Capacity, B.t.u./hr...	+20 (-6.7)	44,700	42,250	1.06
	-20 (-28.9)	15,900	15,660	1.02
	-40 (-40)	7,230	7,000	1.03
Performance Factor, B.t.u./watt hr.	+20	7.10	7.10	1.00
	-20	3.90	4.10	0.95
	-40	2.60	2.60	1.00
Difference from $\text{CHClF}_2/\text{CCl}_2\text{CF}_3$, ° F				
Compressor Discharge Temp., ° F. (° C.)	+20	190 (88)	195 (90.6)	-5
	-20	253 (123)	266 (130)	-13
	-40	284 (140)	302 (150)	-18
Motor Temp., ° F.	+20	115 (46)	107 (42)	+8
	-20	120 (49)	130 (54)	-10
	-40	149 (65)	158 (70)	-9

From Table III, it is apparent that a minimum-boiling azeotrope (i.e., composition having a maximum vapor pressure at any given temperature) exists at about 60% by weight of 1,1,1-trifluoroethane and 40% by weight of chloropentafluoroethane and that the change in vapor pressure of compositions having between 40% and 75% by weight of 1,1,1-trifluoroethane is small.

60 term in which cooling is effected by the evaporation of liquid refrigerant. In such systems, the expanded gas is compressed and condensed to a liquid and is recycled to the evaporator.

65 It will be understood that the specific mixtures employed in the tables are given for illustrative purposes solely and that this invention is not limited to the specific

TABLE III.—VAPOR PRESSURE, IN LBS./IN.² ABSOLUTE, OF
 $\text{CH}_3\text{CF}_3/\text{CCl}_2\text{CF}_3$ COMPOSITIONS IN PARTS BY WEIGHT

Composition →	0/100	25/75	40/60	60/40	75/25	100/0
Temperature, ° F. (° C.):						
53	90.0	122.6	128.6	132.0	131.1	127.0
4				56.7	56.2	54.0

-60	8.17	12.15	12.73	12.93	12.88	12.4

embodiments so used. On the other hand, it will be apparent to those skilled in the art that, subject to the limitations set forth in the general description, many variations can be made in the proportions of the components in the compositions and in the manner, conditions and apparatus in which they are used without departing from the spirit or scope of this invention.

From the preceding description, it will be apparent that this invention provides novel low-boiling refrigerant compositions which have azeotrope-like characteristics and which can be considerably varied in composition without loss of those characteristics. They are particularly useful in refrigeration apparatus which has been designed for the use of chlorodifluoromethane to increase the capacity of such apparatus and to provide a number of other advantages. Accordingly, this invention constitutes a valuable advance in and contribution to the art.

The embodiments of the invention in which an exclusive property or privilege is claimed are defined as follows:

5 1. A low-boiling refrigerant composition which consists of a mixture of from about 40% to about 75% by weight of 1,1,1-trifluoroethane and from about 60% to about 25% by weight of chloropentafluoroethane, said mixture having a normal boiling range of -55° F. to -57° F.

10 2. A low-boiling refrigerant composition which consists of a mixture of 60% by weight of 1,1,1-trifluoroethane and 40% by weight of chloropentafluoroethane, said mixture having a normal boiling point of $-56 \pm 1^{\circ}$ F.

UNITED STATES PATENT OFFICE

Certificate

Patent No. 3,377,287

Patented April 9, 1968

Donovan Erb Kvalnes and Howard Maurice Parmelee

Application having been made by Donovan Erb Kvalnes and Howard Maurice Parmelee, the inventors named in the patent above identified, and E. I. du Pont de Nemours and Company, Wilmington, Del., a corporation of Delaware, the assignee, for the issuance of a certificate under the provisions of Title 35, Section 256, of the United States Code, deleting the name of Howard Maurice Parmelee as a joint inventor, and a showing and proof of facts satisfying the requirements of the said section having been submitted, it is this 22nd day of December 1970, certified that the name of the said Howard Maurice Parmelee is hereby deleted from the said patent as a joint inventor with the said Donovan Erb Kvalnes.
